Patented Aug. 6, 1963

195,935

WATER CONDITIONER

Donald J. Dicktel, Brookfield, Wis., assignor to Bruner Corporation, Milwaukee, Wis., a corporation of Wisconsin

Filed Feb. 18, 1963, Ser. No. 73,591

Term of patent 14 years

(Cl. D91—1)

The single FIGURE is a perspective view of a water conditioner embodying my new design.

The two undisclosed sides of the casing portion, shown in full lines, are identical with the left side shown in the single perspective view.

The dominant features of my design reside in those portions thereof shown in full lines.

I claim:

The ornamental design for a water conditioner, as shown and described.
